UNITED STATES PATENT OFFICE.

WILLIAM TONIE BRIDGES, OF LA FAYETTE, GEORGIA.

THERMOSTATIC CIRCUIT CLOSER.

Application filed May 8, 1923. Serial No. 637,527.

To all whom it may concern:

Be it known that I, WILLIAM T. BRIDGES, a citizen of the United States, residing at La Fayette, in the county of Walker and 5 State of Georgia, have invented new and useful Improvements in Thermostatic Circuit Closers, of which the following is a specification.

This invention relates to a thermostatic 10 circuit closer, which is adapted to be used in connection with a fire alarm system for buildings, and which is operable upon the occurrence of fire conditions to close an electric circuit and sound the alarm.

15 One of the objects of the invention is to provide improved means for closing the electrical circuit upon the destruction of an element, which, when subjected to a temperature which would endanger the building, is 20 either fused or burned so as to release the mechanism which completes the circuit through the alarm.

With the above and other objects in view, which will be apparent from the following 25 description, the invention consists of details of construction which will be described in connection with the accompanying drawings and subsequently claimed.

30 In the drawings:—

Figure 1 is a perspective view of the invention.

Figure 2 is a vertical sectional view thereof.

Figure 3 is a bottom plan view thereof.

35 Figure 4 is a sectional view on the line 4—4 of Figure 2.

Each of the circuit closers 15 includes a cup-shaped housing 18, having a flat rim portion secured to a flat surface 19 of the 40 building by means of suitable screws 20 or the like, and held spaced therefrom by a peripheral flange provided with notches through which the wires pass. A plate 21 is secured transversely of the wires by means 45 of the same screws 20 which secure the housing, and has a raised central portion to which an insulating block 22 is secured. The parallel portions of the wires pass beneath the block 22, and are secured thereto by means 50 of binding posts 23. The ends 24 of the binding posts constitute spaced contact members by the bridging of which a circuit is established.

The under side of the housing 18 is 55 formed with a central perforation 25 around which the housing is turned inwardly to

form a flange 26. A movable contact member 27 is formed from sheet metal and dished to provide an outwardly-extending boss 28 adapted to extend through the perforation 25 and to be secured therein by a retaining pin 29, the inner portion of the member 27 being provided with a peripheral flange 30, which, when the member 27 is released from the pin 29, is adapted to contact with the spaced contact members 24 and bridge the same. An expansile coiled spring 31 is seated within the housing surrounding the flange 26 and presses against the flange 30, urging the contact member 27 toward the spaced contacts 24. The pin 29 may be made of celluloid, lead or any other material which will be fused or burned when subjected to fire. Consequently, as will be readily understood, when fire occurs, the pin 29 will 75 be destroyed, thus releasing the movable contact member 27, which, under the action of the spring 31, will be urged into position to bridge the spaced contacts 24 and establish a circuit. 80

It will be understood that the specific means by which the invention is carried out and the specific arrangement herein described is merely illustrative, and that various modifications may be made therein 85 without departing from the essential principles of the invention, or sacrificing any of the advantages thereof.

What is claimed is:—

1. In a thermostatic circuit closer, the 90 combination of a cup-shaped housing having a rim with a flat portion secured to a surface of the building, said rim having a peripheral flange engaging said surface to hold the flat portion in spaced relation thereto and provided with pairs of opposed notches, main lead wires having portions traversing the housing and passing through said notches, a plate supported within the housing transversely of the wires and having a raised portion underneath which the wires pass and having insulating binding posts extending therethrough to which the wires are secured, said housing having a central perforation, a movable contact normally seated in said perforation and out of engagement with said binding posts, means holding the movable contact in this position but adapted to release the same upon the application of a predetermined degree 100 of heat, and a spring seated in the housing and operable upon the release of said mov. 105

able contact to move the same into engagement with said binding posts.

2. In a thermostatic circuit closer, the combination of a cup-shaped housing having a rim with a flat portion secured to a surface of the building, said rim having a peripheral flange engaging said surface to hold the flat portion in spaced relation thereto and provided with pairs of opposed notches, main lead wires having parallel portions traversing the housing and passing through said notches, a plate located within the housing transversely of the wires and having a raised portion underneath which the wires pass, and having insulating binding posts to which the wires are secured, said binding posts extending through the plate to form spaced contacts on the opposite side thereof, said plate being secured to said surface by the same means which secures the housing, said housing having a central perforation, a movable contact member having a boss normally extending through the perforation, a pin retaining the boss in normal position but adapted to be destroyed when subjected to fire conditions, and means for forcing the movable member into contact with the spaced contact members to com-

plete the circuit when the retaining pin is destroyed.

3. In a thermostatic circuit closer, a housing secured to a fixed support and containing spaced contact members, main lead wires having their terminal portions connected with said spaced contacts, said housing having a perforation beneath said contacts, with an internal flange surrounding said perforation, a movable contact member of sheet metal and dished to form a boss which normally extends through the perforation and is provided with a peripheral flange seated against said internal flange and extending beyond the same, a fusible pin retaining the boss in normal position but adapted to be fused when subjected to fire conditions, and an expansile coiled spring surrounding said internal flange and pressing against said peripheral flange, said spring being operable when the pin has fused to force the movable contact member into position to bridge the spaced contact members to complete the circuit through the lead wires.

In testimony that I claim the foregoing as my own, I have hereto affixed my signature.

WILLIAM TONIE BRIDGES.
